UNITED STATES PATENT OFFICE.

ARTHUR COX, OF OLTON, NEAR BIRMINGHAM, ENGLAND.

CARBURETER.

1,143,511.

Specification of Letters Patent. Patented June 15, 1915.

Application filed September 19, 1912. Serial No. 721,283.

To all whom it may concern:

Be it known that I, ARTHUR Cox, a subject of the King of Great Britain, residing at Rose Hill House, Warwick Road, Olton, 5 near Birmingham, England, process engraver, have invented certain new and useful Improvements in Carbureters for Internal-Combustion Engines, of which the following is a specification.

10 The principal problem which has to be solved in designing a jet carbureter for internal combustion engines is to provide for the production of an efficient or correctly proportioned explosive mixture over a wide 15 range of engine speeds, and with this object in view, many carbureters have been proposed which embody extra-air valves, fuel balancing chambers or the like compensating devices controlled or operated by engine 20 suction to regulate the admission of air or fuel (or both air and fuel) in accordance with the demands of the engine. The majority of such instruments depend, however, 25 for their efficiency on springs or sliding parts which are liable to be affected by dust, wear-and-tear or the like and are consequently unreliable in their action, while their proper adjustment in the event of derangement is a difficult matter, especially in 30 the hands of inexperienced users. Further, these "automatic" carbureters are necessarily complicated in their construction and expensive to produce.

Another difficulty with automatic carbureters of the single jet type is that of obtaining a correctly proportioned mixture at starting or when the engine is running at slow speeds (especially under load) and the flow of air past the jet is of relatively low 40 inductive value, since if the carbureter is fitted with a jet large enough to give a correct mixture at normal and high speeds, the mixture produced at low speeds would be out of "balance" due to excess of fuel, 45 whereas a small jet suitable for passing the correct proportion of fuel at low engine speeds will not pass enough fuel to properly carburet the large volume of air that is drawn in when the engine revolutions are 50 high. Carbureters have therefore been designed with variable jets in which a taper regulating-needle or metering pin is adjustable within the fuel-orifice of the jet to vary the effective size of the said orifice as 55 the air supply is varied or regulated accord-

ing to the volume of mixture required to meet the changing demands of the engine at different speeds, but such jet-varying devices are usually operated automatically by pistons or like sliding parts which are functioned by engine suction and are only indirectly controllable by a driver through some form of throttle valve arranged on the engine side of the carbureter. Moreover, such carbureters generally fail to produce a correctly-proportioned mixture when the controlling members are positioned for starting-up or for slow speed running, owing to the fact that at such settings, the jet orifice is reduced to a small area by the regulating 60 needle while the small volume of air drawn through the instrument by the slow-speed engine suction is of insufficient inductive value to maintain and properly atomize the requisite flow of fuel at the said restricted 65 orifice.

The present invention has for its principal object, to provide for the production of a correctly-proportioned mixture over a wide range of engine speeds (including 80 starting up and slow running) by an extremely simple construction of carbureter of the single variable-jet type, in which all the functions of the instrument are positively governed on the atmospheric side of 85 the mixing chamber by a controlling unit which is operated by the driver from a single lever.

Another object is to provide for the utilization of the whole of the air admitted into 90 the instrument to the best advantage for maintaining an effective fuel-flow at the jet at all engine speeds and under all conditions of working, and for properly atomizing that fuel as it issues from the jet-orifice. 95

Figure 1 of the accompanying drawings represents a side elevation of one form of a petrol carbureter constructed in accordance with my invention. Fig. 2 is a complete vertical section of the carbureter, showing the 100 controlling unit in the position in which it is placed when the carbureter is out of action. Fig. 3 is another section, similar to Fig. 2, but showing the positions which the parts assume when the controlling unit is 105 raised to a point where the sleeve-controlling air-intakes are fully opened by the piston valve member of the said unit. Fig. 4 is another sectional view similar to Figs. 2 and 3, but showing the controlling unit 110

lifted to its highest position in which the air passage round the jet is enlarged to its maximum area. Fig. 5 is a separate elevation of the controlling unit, showing the size and formation of the mixture outlet port. In this view, the shaded area A indicates the formations and relative sizes of the mixture-outlet apertures formed in the piston sleeve of the controlling unit and carburetor casing respectively. Fig. 6 is a section of Fig. 5 upon the dotted line x' . Fig. 7 is a section of the regulating sleeve, separately. Fig. 8 is a vertical section, on an enlarged scale, of the lower part of the carburetor, and shows the construction of the jet. Fig. 9 is a horizontal section on the dotted line x^2 showing, in plan, the air and fuel orifices of the jet. Figs. 10 and 11 show elevations and sections of two different forms of fuel regulating needle which may be adopted for varying the effective area of the fuel orifice of the jet. Fig. 12 is a section of an alternative or modified construction of the improved carburetor: the same being designed for use in connection with motor-cycle engines. Figs. 13, 14 and 15 show various modified forms of air-intake ports which may be adopted in place of the ports shown in Figs. 1 to 4.

30 Describing first the construction shown in Figs. 1 to 8: a is a cylindrical casing, which has connection, at its base, with a fuel-passage a^2 leading from an ordinary float chamber and communicating with the jet f . This base is also provided with a series of primary air-intakes d wherethrough air is drawn from a supply pipe such as d^1 into a conical sleeve e which surrounds the said jet and whose upper end has communication 35 with an annular air passage surrounding the fuel orifice of the said jet, as hereinafter further described.

40 Secondary air-intakes wherethrough the bulk of the air for forming the mixture is admitted are formed in the lower part of the casing at g so that they may be progressively opened and closed by the lower part of the piston-valve sleeve h . The secondary intakes may be made in various 45 forms as hereinafter described, but those shown in Figs. 1, 2, 3, 4 and 8 comprise rectangular apertures g^1 of relatively large area and a series of small V-shaped apertures g^2 which depend below the apertures g^1 and are 50 therefore adapted to be opened or uncovered by the valve member during its initial lifting movement. The special functions of these ports will be further referred to in describing the operation of the carburetor.

55 The said valve sleeve member h , is closed at its upper end, open at its lower end, and is capable of a free sliding movement within the casing, and its dimensions are such that when placed at its lowest position in the said 60 casing, its unperforated lower end h' en-

tiely closes the air-intakes g while its unperforated upper part h^2 closes the outlet a^4 wherethrough the carburetor has communication with the induction pipe of an engine except for a by-pass communication with 70 said outlet to be hereafter referred to. Below the part h^2 there is an opening h^3 which, as the sleeve is adjusted within the casing for altering the mixture-producing capacity of the instrument is brought more or less in 75 to register with the mixture outlet port a^4 in the side of the said casing. This outlet port arrangement, however, has no controlling effect, and, in practice, the opening h^3 is so formed that at any setting of the sleeve, 80 it provides a mixture outlet port whose area exceeds the cross sectional area of that port of the Venturi-tube where the air stream has its greatest velocity.

85 The adjustable choke tube i is of the Venturi-type and is secured within the lower end of the sleeve member h . This choke tube surrounds and is adjustable relatively to the fixed cone e , and the annular space between the two members i , e , constitutes the 90 air passage wherethrough the whole of the air admitted at both the secondary ports g and the base ports d is conveyed in a stream line formation around the orifice end of the jet. The form of tube shown in the drawings is so arranged that, when the controlling 95 unit is set in its closed position (Fig. 2) its throat i' is situated in approximately the same plane as the fuel orifice f^2 and the air passage between the members i and e is 100 reduced to its minimum capacity, but as the control unit is lifted by the operating lever, the said air passage is progressively increased in size and is thereby adapted to pass a greater volume of air with each increment of lift, until by the time the unit has 105 been raised to the limit of its lifting movement (see Fig. 4) the sectional area surrounding the orifice end of the jet-barrel attains its maximum size.

110 In conjunction with the adjustable valve sleeve and choke-tube above described, I may use any suitable construction of jet which will admit of the adjustment of the effective size of the fuel orifice by means of a needle 115 or metering pin connected to and operated from the said sleeve, but in the drawings, I have shown an arrangement wherein the primary air drawn through the bottom intakes d is utilized to assist atomization of fuel 120 when the carburetor is set for low-speed running. This jet construction comprises a cylinder or barrel f^1 of relatively large bore and adapted to contain a considerable volume of fuel, while the outlet f^2 consists of a 125 short passage of much smaller bore than the said barrel f^1 . The upper end of the barrel is coned externally at f^3 and is fitted with a screwed-on cap f^4 , which has a flat top, while its interior is shaped substantially as shown, 130

so that there is provided between the said cap and the barrel-cone f^3 , an annular air-passage f^4 whose outlet f^5 (which is of very small area) concentrically surrounds the fuel-orifice f^2 . To admit air into this passage, the base of the cap is drilled with a series of apertures f^6 communicating with the cone e , whose upper end fits closely around the said cap; the arrangement being such that the primary air drawn into the cone e , and through the holes f^6 into the passage f^4 , is discharged through the small concentric outlet f^5 , around and in close proximity to the fuel orifice f^2 .

To vary the area of the fuel aperture f^2 , and so provide for the regulation of the fuel supply simultaneously with the other adjustments of the instrument, the sleeve h has connected with it, a long slow-tapered valve-needle j , which is guided by a tubular extension f^8 from the crown of the barrel jet, and extends axially through the fuel orifice f^2 . This needle is of such a length that, whatever may be the position of the sleeve h , there is always a portion of the said needle depending through the said orifice f^2 .

This needle may have any suitable tapering formation, but in cases where it is required to increase the area of the fuel orifice *pro rata* with the lift of the valve sleeve and choke tube, the effective part j^1 of the needle has a regularly diminishing taper from end to end (see Fig. 11) but in another case, the needle has a double taper so that as it is lifted with the sleeve, it shall first gradually increase the area of the jet-aperture and then (if and when the said sleeve is lifted beyond a certain predetermined point) progressively reduce or throttle the same. This latter formation is shown in Figs. 2, 3, 4 and 10, where the two reverse taper portions are marked j^1, j^2 .

One object in using a large-bore or barrel jet f having a short orifice of relatively small bore, is to guard against possible disturbance of the mixture due to the inertia of the fuel-flow through the said orifice not being reduced in synchronism with reductions in the area of the said orifice and of the choke-tube area surrounding same, since when the carburetor is in action, fuel is only set in motion at a high speed for a distance corresponding to the depth of the orifice f^2 while the main bulk of fuel contained in the enlarged or barrel part of the jet can move but slowly and is not affected by the inertia set up in the relative short and small bored aperture f^2 . The chambered jet also has the advantage that, since the walls are thin and fuel remains in the chamber for an appreciably longer time than it would if an ordinary parallel-bored jet was used, the said fuel may be raised in temperature when hot air is drawn through the surrounding cone e .

and its subsequent vaporization is thereby assisted. Further, by using a large-diameter barrel jet which is located axially in the choke-tube and has a flat upper end, when air is passing through the said choke-tube, 70 a region of depression or partial vacuum is formed above the fuel orifice in the said flat end and the induction of fuel through the said orifice is thereby assisted.

The positively-operated valve-needle may 75 be detachably and adjustably connected, by a screw and lock-nut or like arrangement, to the top of the valve sleeve for the purpose of predetermining the degree of opening that shall obtain at the fuel orifice with any given 80 lift of the controlling unit and also to enable either a single-taper, double-taper, or other suitable needle being interchangeably fitted, as desired, for adapting the carburetor to suit different engines. 85

Any suitable mechanical arrangement may be provided in connection with the regulating sleeve to provide for the latter being positively raised and lowered from a single lever under the direct control of a driver. 90

To avoid any abrupt change of direction in the flow of mixture through the carburetor, the upper part of the valve sleeve is provided with an inclined or curved surface m^1 which guides or directs the mixture stream from the interior of the said sleeve toward the outlet port h^3 , the said surface, in the embodiment shown, being formed on a filler piece m of suitable light material. 95

To enable an engine to be started when the valve sleeve is in its closed position and the secondary air-intakes are shut, and also to enable the carburetor to produce a mixture suitable for slow running under light load, the cone e which communicates with the primary air-ports d is pierced with a few small perforations k , while the filler-piece m in the crown of the valve sleeve h is formed with a small-bore passage k' which (when the said sleeve h is closed and also during the initial part of its lifting movement) establishes a by-pass connection between the interior of the carburetor and outlet port a^4 in the casing. 100 105 110

A regulating screw such as k^2 may be provided for adjusting the area of the outlet end of the said passage, and the arrangement is such that when an engine is turned for starting (the various parts of the carburetor being in the positions shown in Fig. 2) its suction, acting through the passage k' , draws air through the ports d into the cone e whence a portion of the air passes through the perforations k into the choke-tube, while another portion is drawn through the passage f^4 and through the small annular outlet f^5 and serves to atomize the fuel as the latter is induced through the restricted jet-orifice f^2 . This produces a small quantity of mixture which is conveyed to the engine 115 120 125 130 135

through the by-pass k' , and the power developed by its combustion in the cylinders serves to keep the said engine running under light load until the main carburetor is put into operation by the lifting of the valve sleeve, but when the said sleeve has been raised above a certain point and the main carburetor is functioning to supply the engine with mixture, the passage k' is taken out of register with the outlet port a^4 , and the internal by-pass is thereby cut out of action.

Referring again to the air-intake ports g in the lower walls of the casing a : the V-shaped extensions g^2 thereof are of such form and dimensions that, during the initial lifting movement of the valve member (i. e. during its movement over a linear distance equivalent to the depth of the said V-shaped ports) the aggregate area of opening which is provided for the admission of air is less than the prevailing cross-sectional area of the air-passage o surrounding the jet-orifice, and therefore also less than the area of the mixture-outlet port on the engine side of the mixing chamber. Consequently during this part of the working range of the instrument, the valve-controlled openings g^2 function as one of the atmospheric-side governing factors whereby effective atomization and carburation is attained. The larger rectangular parts g' of the said ports are, however, of such dimensions that, on the valve being lifted beyond the apertures g^2 the aggregate area of opening produced at g' , g^2 exceeds the cross sectional area of the air passage o so that throughout the remainder of the working range of the controlling unit, the said port provides for a free or unthrottled admission of air to the choke tube which functions as the quantity-governing factor.

With further regard to the arrangement of the mixture-outlet port: it is to be understood that the instrument herein described is controlled entirely from the atmospheric side of the mixing chamber and does not depend for its effective operation on the interposition of any form of "throttle" valve between the said mixing-chamber and the engine. Therefore, although the drawings show two relatively movable apertures h^3 , a^4 that constitute an adjustable outlet port whose area varies with the adjustment of the air-passage, this arrangement is merely adopted as a matter of constructional convenience and the carburetor would function equally well with a non-variable outlet port having an effective area equal to or exceeding the maximum sectional area of air-passage obtainable when the choke-tube is lifted to the limit of its movement.

With a carburetor constructed as above described the engine may, if desired, be set running by using the by-pass arrangement

when the parts are in the position shown in Fig. 2 and all the passages through the main part of the instrument are closed.

Then on proceeding to lift or adjust the controlling unit so that the valve member commences to uncover the V-shaped extensions g^2 of the air-intakes g while the simultaneous adjustment of the choke-tube enlarges the main air-passage (see Fig. 3) the carburetor functions to produce a mixture which will enable the engine to develop the power necessary for running at slow speeds under load. During this part of the working range of the unit (i. e. for any setting within limits corresponding to the depth of the V-apertures g^2) the air-intake area provided by the uncovered portions of the said apertures g^2 is less than the area of the air passage at o and consequently the said valve-regulated apertures more or less throttle or restrict the incoming air and so function as an atmospheric-side controlling factor that enable the engine-suction prevailing at such low-speed settings to produce and maintain a higher internal negative pressure than would be obtainable if air was admitted without restriction at the intakes. And therefore, although the jet-orifice is restricted to a small size by its regulating needle and although the choke-tube setting provides only a small air-passage between itself and the cone e the enhanced negative pressure causes the air to pass at a high speed through the choke-tube and also exerts a strong pull or suction on the said restricted jet-orifice, so that not only is the fuel induced from the jet in a regulated quantity proper to form a correctly proportioned mixture with the prevailing air-flow, but it is also completely atomized by the strong inductive suction and is moreover, discharged into the surrounding air stream at the point where the latter attains its maximum velocity (i. e. at the point o where the air-passage through the choke-tube has its minimum cross-sectional area) with the result that the perfectly atomized fuel is thoroughly incorporated with the air and the mixture supplied to the engine is of a character that will enable the same to develop at a low revolution rate and on a minimum fuel consumption, sufficient power to take up and pull its load.

But during the uncovering of the apertures g^2 by the piston valve, the relative areas of the air-ports and air passage at o are not varied on the same ratio, as owing to the V-formation of the said apertures, they provide for the enlargement of the intake-port area in an increasing proportion relative to the enlargement of the said air passage, and consequently, as the ports are opened up by the lifting of the piston valve with the Venturi-tube their air-throttling effect is modified or lessened and the value

of the internal negative pressure is reduced. That is to say, although throughout the entire range of low speed adjustments, the carburetor is made to function under an enhanced negative pressure as the direct result of the action of the valve-regulated apertures g^2 yet the shaping of the said apertures provides for the regulation or variation of the value of the said negative pressure simultaneously with the variations of the air-passage and fuel-orifice areas, so that as the mixture producing capacity is enlarged and the velocity and fuel-inducing value of the air stream at the area o is correspondingly increased, the value of the negative pressure factor is reduced or lessened to balance the increase in value of the air-velocity factors being such—at all settings within the limits of the low speed range—as will keep a proper suction on the needle-adjusted jet-orifice without tending to induce too great a discharge of fuel and so upset the proportion of the mixture.

But when the working capacity of the carburetor is increased for producing a greater volume of mixture by lifting the controlling unit to such a position that the lower edge of the piston-valve comes above the upper ends of the V-apertures g^2 and commences to open up the rectangular ports g' (see for instance Fig. 4) the carburetor ceases to operate on the enhanced negative pressure principles, since for all settings above the position shown in Fig. 3, the aggregate intake-port opening produced by the open V-apertures plus the uncovered areas of the apertures g' exceeds the cross-sectional area of the annular air-passage at o . Consequently, and as the air is no longer throttled or restricted at the intake, the negative pressure is maintained by engine suction alone and therefore has a constant value, and the volume or quantity of mixture produced at any given setting or capacity adjustment of the instrument is governed only by the choke-tube and engine speed, while as regards the fuel supply, the regulating needle adjustment provides a jet of appropriate working or effective size for each and every air-capacity adjustment, so that by the combined effect of the depression produced by engine suction and the powerful inductive action of the high-velocity air-stream (which attains its highest speed at the area o except when the controlling unit is raised to the limit of its movement as shown in Fig. 5) a supply of fuel, sufficient to correctly carburet the air supply at any engine speed within the limits imposed by the choke-tube adjustment, is discharged in a properly atomized condition into the said air stream in the region of the said maximum velocity area o .

Thus when the engine is working under constant negative pressure principles, its

mixture-producing capacity and the fuel-inducing and atomizing value of the air-stream speed are directly and positively controllable by the Venturi-tube adjustments only, so that merely by raising or lowering the controlling unit a driver can, without disturbing the balance of the mixture, directly and positively govern the engine speed according to the power required to meet varying loads or other conditions of running.

But when the unit is lifted to the position shown in Fig. 5 and the air and fuel passages are enlarged to their maximum sizes to provide for "all-out" running at high speeds or for powerful pulling under heavy loads, the volume of mixture produced, and the velocity and inductive value of the air flow at the jet-orifice is practically governed by engine speed alone. Indeed, it may be said that, at this setting, carburation is no longer regulated by the controlling unit but merely proceeds in accordance with the demands of the engine; and although the quantity and velocity of the air flow varies as the engine-speed fluctuates with varying conditions of load, the jet-orifice is open-up to such size as will enable the air—whatever its volume may be—to take up and atomize the proportion of fuel required for its correct carburation.

Any of the modified form of secondary air-intake ports represented in Figs. 13, 14 and 15 may be used instead of the formation shown in Figs. 1, 2, 3, 4 and 5, or I may use any other shape or arrangement of apertures which will function to govern or control, from the atmospheric or intake side of the instrument, the value of the internal negative pressure in the manner and for the purpose herein described.

In the alternative construction shown in Fig. 12 (which is suitable for use in connection with motor-cycle and like engines) the air intakes d in the bottom of the casing are dispensed with: the only air-ports being those which are formed at g in the lower part of the said casing and are opened and closed by the regulating sleeve h .

The jet and fuel-regulating devices are of substantially the same construction as the corresponding parts in the arrangement illustrated in Figs. 1 to 10, and the choke-tube i in the lower part of the sleeve h is also of such dimensions as to provide for the desired infinite variation of the area surrounding the fuel orifices throughout the whole range of movement of the said sleeve, so that when the sleeve and choke are set for starting or slow running, the smallest area of the choke-tube is brought into effective relation with the fuel orifice, which is restricted to its minimum size by the fuel-regulating needle, while for each successive increment of lift, the area of the choke-tube

is, as in the previously described arrangement, enlarged simultaneously with the adjustment of the fuel orifice for keeping the air suction or friction of practically constant value and providing a fuel flow which will, with the prevailing air-flow, produce a mixture of the best proportions.

Having described my invention, what I claim and desire to secure by Letters Patent is:—

1. A carbureter for internal combustion engines, comprising a casing and a positively operated adjustable regulating sleeve which is combined with a choke tube and a fuel regulating needle, the said casing being provided with a system of intakes through which air is admitted under the control of said sleeve which are so formed that, during the starting lift of the sleeve, they restrict the admission of air, whereas when the lift is continued beyond the starting position, the said ports provide for an unrestricted air admission, substantially as and for the purpose described.
2. A carbureter comprising a casing with secondary intake ports and a mixture outlet, and a positively-operated adjustable regulating sleeve controlling said intake ports and carrying a choke-tube and a fuel-regulating needle, in combination with a jet having an annular air passage which communicates with other air-intakes and has an outlet closely surrounding the fuel orifice of the said jet, substantially as and for the purpose described.
3. A carbureter comprising a casing with secondary air-intake ports and a mixture outlet, and a positively-operated adjustable regulating sleeve controlling said intake ports and carrying a choke-tube and a fuel-regulating needle, in combination with a jet having an annular air passage whose outlet closely surrounds the fuel orifice of the said jet, and which is supplied with air from a sleeve that surrounds the said jet and communicates with other air-intakes in the carbureter casing, substantially as and for the purpose described.
4. A carbureter comprising a casing having secondary air-intake ports and a mixture outlet, a positively-operated regulating sleeve, controlling said intake ports, the casing having other air-intake ports which are constantly open to the interior of the said sleeve, in combination with a by-pass leading from the upper part of the regulating sleeve and adapted to establish communication (when the said regulating sleeve is fully closed) between the last named air-intake ports and the outlet in the casing, substantially as and for the purpose herein described.
5. A carbureter for internal combustion engines, comprising a casing provided with a system of air intakes, a positively operated

regulating sleeve adapted to vary the areas of the said air intakes, in combination with a Venturi-type choke-tube which is adjusted in its relation to the fuel orifice of the jet by the said regulating sleeve, a fuel regulating needle which is also adjusted by the said sleeve and engages with the said fuel orifice, the sleeve, the choke tube, and the needle being movable as a unit, and means for positively moving the sleeve lengthwise of the casing to effect the adjustment aforesaid, said air intakes being so formed that, during the starting lift of the sleeve, they restrict the admission of air, whereas when the lift is continued beyond the starting position, said parts provide for an unrestricted air admission, substantially as and for the purpose described.

6. In a variable jet-carbureter: the combination with a casing having a mixture outlet and a system of air intake ports at its lower end and a fuel-jet arranged within the casing of a controlling unit which is adjustable in the said casing and comprises a needle engaging the fuel orifice in the top of the jet and serving to regulate the fuel-supply, a Venturi-type choke-tube surrounding the said jet and functioning to vary the cross sectional area of the air-passage around the jet-orifice, and a valve-sleeve co-operating with said system of air-intake ports, the said ports being so formed that, when the choke-tube is adjusted for small mixture-producing capacities, they throttle or restrict the air-supply and thereby enable the engine suction to maintain an increased or enhanced negative pressure in the region of the jet-orifice, whereas when the instrument is adjusted for larger capacities, the said ports provide for a free or unrestricted air-admission, substantially as described.

7. In a variable-jet carbureter; the combination with a casing having a mixture-outlet and a system of air intake ports at its lower end, a central jet arranged within the casing and a fixed cone surrounding said jet of a positively-adjustable controlling unit, comprising a fuel-regulating needle engaging a fuel-orifice in the crown of the jet, a Venturi-type choke-tube which surrounds the fixed cone and is adjustable relatively thereto for varying the size or capacity of the air-passage between itself and the said cone, and a valve-sleeve co-operating with said system of air-intake ports, the form and dimensions of the said ports being such that, by and during adjustments of the controlling unit for slow engine speeds, they are opened to an aggregate area less than the cross-sectional area of the air-passage surrounding the fuel-orifice, whereas during adjustments for higher engine speeds, the said ports provide an aggregate air-admission area exceeding the area of the said air-

passage around the orifice, substantially as and for the purposes herein described.

8. In a single-jet carbureter; the combination with a casing having a mixture-outlet and a system of air-intake ports at its lower end, and a fuel-jet arranged within the casing of an adjustable controlling unit embodying a fuel-regulating needle engaging the jet-orifice, a Venturi-type choke-tube surrounding the said jet and functioning to vary the cross-sectional area of the air-passage surrounding the said orifice, and a valve sleeve that serves to vary the area of said air-intake ports, each of the said ports consisting of one or more substantially V-shaped apertures which are opened during adjustments of the controlling unit for low engine speed and provide an aggregate air-admission area less than the prevailing area of the air passage around the jet orifice, and relatively larger areas which are also opened up by adjustments of the said unit for higher engine speeds to provide an aggregate air-admission area that exceeds the prevailing air-passage area at the jet-orifice, substantially as described.
9. A single-jet carbureter consisting of a casing provided with a mixture-outlet and having at its lower end a system of air-intake ports, each of which has one or more V-shaped apertures at its lower side, a chambered or barrel jet which is adapted to contain a relatively large volume of fuel and has a jet-orifice of smaller bore than the

fuel chamber, and a controlling unit comprising a fuel-regulating needle engaging the jet orifice, a Venturi-type choke-tube surrounding the barrel-jet, and a valve sleeve coöoperating with the air-intake ports of the casing to regulate the admission of air through the said ports, substantially as and for the purpose herein set forth.

10. A single-jet carbureter, comprising a casing provided with a mixture-outlet and having at its lower end a system of air-intake ports, each of which has one or more V-shaped apertures at its lower side, a jet supported from the base of the said casing, a fixed cone surrounding the said jet, the casing having other air-intake ports in its base and communicating with the interior of the cone, and an air-outlet leading from the said cone into the main air-passage, in combination with a controlling unit consisting of a fuel-regulating needle, a Venturi-type choke-tube surrounding the fixed cone, and a valve-sleeve coöoperating with the first named air-intake ports for regulating the admission of air therethrough, substantially as and for the purpose herein set forth.

In testimony whereof I have hereunto set my hand in presence of two subscribing witnesses.

ARTHUR COX.
